Sept 19, 1882

UNITED STATES PATENT OFFICE.

WILLIAM TWEEDDALE, OF BROOKLYN, ASSIGNOR TO THE J. L. MOTT IRON WORKS, OF NEW YORK, N. Y.

DESIGN FOR A FIRE-PLACE.

SPECIFICATION forming part of Design No. 13,308, dated September 19, 1882.

Application filed August 11, 1882. Term of patent 7 years.

To all whom it may concern:

Be it known that I, WILLIAM TWEEDDALE, of Brooklyn, in the State of New York, have invented a Design for Fire-Places, of which

5 the following is a specification.

This design relates to a series of panels, with birds and leaflets forming the base of the fender and the fire-place frame, as shown in the drawing. Each main panel or section is square, or 10 nearly so, with a border. The ornamental figures within the border represent an owl, sunflower, and leaflets at *a*, a bird, leaflet, and stem ornaments at *b*, and flower and leaflet ornaments, as at *c*. The intermediate long 15 narrow panels, *d*, have quadrifol ornaments. These panels are applied, as shown, around the base of the fender between the bar *e* and base *f*, also around the fire-place frame, as shown. There are also corner ornaments *h* on 20 the fire-place frame. Upon the fender, between the bars *e* and *k*, are the balustrade-rails *l*, ornamented as shown, and there are center and corner posts, *m*, with top ornaments. The andirous are ornamented with a round

flower, *n*, at the top, diagonal bars and radial 25 leaflets at *p*, arched and scroll bases at *q*, and quadrifol ornaments at *r*.

The fender piece, fire-place frame, and andirons make up a harmonious design as a whole for a fire-place.

30

I claim as my invention—

1. The design of the birds, leaves, and stems of the panels *a b*, as described and shown.

2. The design of the fender-piece, consisting of the panels *a b c*, base *f*, rails *e k*, balustrade- 35 rails *l*, and posts *m*, substantially as shown.

3. The design of the fire-place frame, composed of the ornamented panels *a b d* and corner-pieces *h*, as represented.

4. The design of the andirons, consisting of 40 the round ornaments *u*, diagonal bars, and radial leaflets, as represented.

Signed by me this 7th day of August, A. D. 1882.

WILLIAM TWEEDDALE.
